DESIGN FOR A FOOD MIXER

Alvar Lenning, Stockholm, Sweden, assignor to Aktiebolaget Elektrolux, Stockholm, Sweden, a corporation of Sweden

Application August 21, 1940, Serial No. 94,538
In Sweden April 3, 1940

Term of patent 14 years

To all whom it may concern:

Be it known that I, Alvar Lenning, a subject of the King of Sweden and a resident of Stockholm, Sweden, have invented a new, original, and ornamental Design for a Food Mixer, of which the following is a specification, reference being had to the accompanying drawing, forming a part thereof, and in which:

Fig. 1 is a side perspective view of a food mixer,
showing my new design;

Fig. 2 is a perspective view of the opposite side
of the same;

Fig. 3 is a perspective view looking from the left of the view shown in Fig. 1; and

Fig. 4 is a top perspective view of the food mixer illustrated in the preceding figures.

I claim:

The ornamental design for a food mixer, as shown.

ALVAR LENNING.
